CLAIM

We claim the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the first image in a sequence for the display screen or portion thereof with animated graphical user interface of FIG. 1 in which a display screen is provided in broken lines to illustrate an example environment;

FIG. 10 is the second image thereof;

FIG. 11 is the third image thereof;

FIG. 12 is the fourth image thereof;

FIG. 13 is the fifth image thereof;

FIG. 14 is the sixth image thereof;

FIG. 15 is the seventh image thereof; and,

FIG. 16 is the eighth image thereof.

The stippled shading of the display screen or portion thereof with animated graphical user interface shown in figures forms part of the claimed design.

The broken lines in the figures show portions of the display screen or portion thereof with animated graphical user interface which form no part of the claimed design.

The broken line showing of the display screen in FIGS. 9-16 are for environmental purposes only and form no part of the claimed design.

The dot dash lines in the figures represent an unclaimed boundary line and form no part of the claimed design.

The appearance of the animated graphical user interface sequentially transitions between the images shown in FIGS.

(Continued)

1-8 and in FIGS. 9-16. The process or period in which one image transitions to another forms no part of the claimed design.
